UNITED STATES PATENT OFFICE.

BENJAMIN F. SCHMIDT, OF LOS ANGELES, CALIFORNIA, ASSIGNOR OF ONE-HALF TO
CHARLES W. SCHMIDT, OF LANKERSHIM, CALIFORNIA.

CASEMENT HINGE.

Application filed September 30, 1925. Serial No. 59,718.

My invention has to do with a novel form of casement hinge. It is sometimes desirable to leave a door or casement window partially open for obtaining ventilation. The door 5 or window should be secured so that it will not swing from the desired position.

It is an object of this invention to provide a hinge for door and casement window use in which the hinge members thereof may be 10 locked in a desired position, thus securing the window or door pivoted thereby in a certain position.

It is another object of this invention to provide a hinge having a pair of members 15 hinged together, each having a clamp plate associated therewith and having means for clamping said clamp plates together.

Other objects and advantages of the invention will be made evident hereinafter.

Referring to the drawings in which I illustrate my invention:

Fig. 1 is a diagrammatic view showing the utility of the casement hinge of my invention.

Fig. 2 is an elevational view of the casement hinge of my invention.

Fig. 3 is a section taken on the line 3—3 of Fig. 2.

Fig. 4 is a fragmentary section showing 30 the manner in which the hinge members are clamped so as to be relatively non-swingable.

In Fig. 1 I show a casement 11 surrounding an opening 12 which is closed by a swinging member such as a door or casement window 13. The member 13 is hingedly secured to the casement 11 by means of a casement hinge 15 incorporating the features of my invention.

With reference to Fig. 2 the hinge 15 has a primary hinge member 18 and a secondary hinge member 19. The primary hinge member 18 is preferably secured to the casement 11 by means of screws 20 which are projected into the casement 11 through openings 21 provided in the primary member 18. The secondary hinge member 19 is secured to the member 13 by screws 23 which are extended into the member 13 through openings 24 provided in the secondary hinge member 19. The primary hinge member 18 has a pair of outer cylindrical portions 25 and the secondary hinge member 19 has a central cylindrical portion 26 which is placed 50 between the outer cylindrical portions 25 of

the primary hinge member 18. A hinge pin 27 is extended through the cylindrical portions 25 and 26 of the primary hinge member 18 and the secondary hinge member 19 for hingedly attaching these members together. A plug 28 is inserted into the lower part of the lower cylindrical portion 25 of the primary hinge member 18. The hinge pin 27 is preferably secured rigidly to the lower outer cylindrical portion 25 of the primary hinge member 18.

The primary hinge member 18 is provided with a notch 30 and the secondary hinge member 19 is provided with a notch 31 which aligns with the notch 30, as clearly shown in Fig. 2. Placed in the notches 30 and 31 concentric with respect to the hinge pin 27 is a lower clamp plate 33 the hinge pin 27 extending through a central threaded opening 34 of the lower clamp plate 33. As clearly shown in Fig. 4, the lower part of the pin 27 is smaller in diameter than the upper part, which upper part is threaded at 35 to permit the lower clamp plate to be secured thereto. The primary hinge plate 18 has a projection 36 which extends and fits loosely in a slot 37 formed in the periphery of the lower clamp plate 33. A lower face 38 of the clamp plate 33 engages a face 39 of the primary hinge member 18, which face 39 defines the lower part of the notch 30. An upper clamp plate 41 is placed in the notches 30 and 31, having a concentric opening 42 through which the pivot pin 27 extends. The upper clamp plate 41 has a slot 43 into which a projection 44 of the secondary hinge member 19 extends, this projection 44 fitting loosely in the slot 43. An upper face 46 of the upper clamp plate 41 is engaged by a face 47 of the secondary hinge plate 19 which confines the upper part of the notch 31. A lower face 49 of the upper clamp plate 41 is adapted to rest in engagement with the upper face 50 of the lower clamp plate 33.

When the hinge is in non-clamping position, as shown in Fig. 2, there is a space 52 between the lower face 38 of the lower clamp plate 33 and the secondary hinge member 19, and there is a space 54 between the upper face 46 of the clamp plate 41 and the lower face of an arm 55 of the primary hinge member 18.

The upper end of the pivot pin 27 is threaded as indicated at 57, and a clamp nut 58 is threaded thereonto, a lower face 59 of

the nut 58 engaging an upper face 60 of the arm 55 of the primary hinge member 18.

In Figs. 1, 2 and 3 the primary and secondary hinge members of my invention are not clamped together and therefore the member 13 is free to swing on its pivot. When it is desired to retain the member 13 rigidly in a certain position, the nut 58 is advanced downward on the upper end 57 of the pivot pin 27 so that the parts occupy a position, as shown in Fig. 4. With reference to Fig. 4, when the nut 58 is advanced downward on the pivot pin 27, the pivot pin is moved upward relative to the parts of the hinge. Since the lower clamp plate 33 is rigidly secured thereto it is moved upward with the shaft. The upper clamp plate 41 is lifted by the lower clamp plate 33 and is brought into engagement with the lower face of the arm 55.

At this time the upper face 50 of the lower clamp plate 33 is forced firmly into engagement with the lower face 49 of the upper clamp plate 41. Sufficient friction is thereby obtained between these two faces to prevent a relative swinging of the primary and secondary hinge members 18 and 19 which are locked to the lower and upper clamp plates 33 and 41, and therefore the member 13 is locked in any desired position as indicated by dotted lines 64 in Fig. 1.

From the foregoing description the utility of my invention is plainly evident. The design of the hinge 15 is rather attractive and can be made in any proportion to suit the needs. The nut 58 is so situated that it is easily operated and the hinge may be readily locked in any desired position. The different parts of my invention are readily assembled and dismantled. It is preferable to make the threads on the lower part of the enlarged portion of the hinge pin 27 coarser

than the threads 57 at the upper end thereof so that in operating the nut 58 the hinge pin will not be loosened in the opening of the lower clamp plate 33.

I claim as my invention:

1. A hinge of the class described comprising: a primary hinge member; a secondary hinge member; a hinge pin by which said primary and secondary hinge members are hingedly secured together; a lower clamp plate adapted to be engaged by and moved with said primary hinge member; an upper clamp plate adapted to rest in engagement with said lower clamp plate, said upper clamp plate being adapted to be engaged by and to move with said secondary hinge member; and means for clamping said upper and lower clamp plates from relative rotation, said primary and secondary hinge members having adjacent notches into which said upper and lower clamp plates extend.

2. A hinge of the class described comprising: a primary hinge member; a secondary hinge member; a hinge pin by which said primary and secondary hinge members are hingedly secured together; a lower clamp plate adapted to be engaged by and moved with said primary hinge member, said hinge pin being rigidly secured to said lower clamp plate; an upper clamp plate adapted to rest in engagement with said lower clamp plate; said upper clamp plate being adapted to be engaged by and to move with said secondary hinge member; and a nut adapted to be advanced onto a threaded end of said hinge pin in a manner to force said lower clamp plate into non-movable contact with said upper clamp plate.

In testimony whereof, I have hereunto set my hand at Los Angeles, California, this 24th day of Sept. 1925.

BENJAMIN F. SCHMIDT.
